(57) **CLAIM**

The ornamental design for packaging with surface ornamentation, as shown and described.

DESCRIPTION

FIG. 1 is a perspective view of packaging with surface ornamentation of the present invention;

FIG. 2 is a top view thereof;

FIG. 3 is a bottom view thereof;

FIG. 4 is a right view thereof;

FIG. 5 is a left view thereof;

FIG. 6 is a front view thereof; and,

FIG. 7 is a rear view thereof.

The broken lines depict environmental subject matter only and form no part of the claimed design.
